UNITED STATES PATENT OFFICE

FRANCIS T. JOHNSON, OF CHICAGO, ILLINOIS

RACK

Application filed March 15, 1930. Serial No. 435,991.

This invention relates to a rack which is movably mounted and which is adapted to have material hung upon it. In the form illustrated, it is particularly designed for application to an enclosed space such as a closet or dryer.

One object of the invention is to provide a combined rack and door support upon which clothing may be suspended and which will be movable and which will serve also as a support for the door. Another object is to provide such a support so that when the door is open, the door, the support and the associated parts do not sag and are held in a level position.

Other objects will appear from time to time in the course of the specification and claims.

My invention is illustrated more or less diagrammatically in the accompanying drawings, wherein:

Figure 1 is a vertical cross section through a dryer to which my invention has been applied, with the door closed;

Figure 2 is a similar view with the door open;

Figure 3 is a detailed vertical cross section on an enlarged scale, taken at line 3—3 of Figure 1;

Figure 4 is a detailed vertical cross section on an enlarged scale taken at line 4—4 of Figure 1;

Figure 5 is a horizontal detailed cross section on an enlarged scale, taken at line 5—5 of Figure 2, looking up in the direction of the arrows.

Like parts are designated by like characters throughout the specification and drawings.

The housing or casing for the dryer is made up of suitable members. It may, for example, include walls A, a top or roof A¹, an end or rear closing plate A² and a door or front closing member A³. It is this latter part which is supported for movement by the rack which will be described below.

A⁴ is a member which may be generally parallel to the member A³. It and the member A³ together are joined by one or more rods or tubes A⁵ on which material may be suspended. These rods or tubes may be hollow as indicated in Figure 2 at A⁶ and heated fluid such as air, steam or water may be supplied to the interior of the tubes so that the garments or other material which they support will be heated. This feature is not an essential part of the present invention and the invention is not limited to it. The connections by which such heated fluid is supplied to the tubes are not shown.

B is a member preferably having an angular shape. It is fastened at one end to the door member A³, for example by means of bolts B¹ or any other suitable manner. Preferably adjacent its rear end it has a downwardly depending member B² to which the member A⁴ is fastened by bolts or other suitable fastenings B³. At or near its rear end the member B carries a roller B⁴ which is suitably supported by bearing members generally indicated by the letter B⁵. B⁶ is a reinforcing part for the member B which is fastened to the side of the member at one end adjacent the support of the roller B⁴. At its other end the member B⁶ is laterally bent as at B⁷ and may provide a stop to limit the outward movement of the door as indicated in Figure 2. The horizontal flange of the member B is cut away adjacent the roller as at B⁸ so that the roller may extend beyond the flange at this point.

C is a channel which is provided with a downwardly depending lip or flange C¹ and is fastened to the top or roof of the dryer as at C² C³. Adjacent its further end the lower flange of the channel C is cut away as at C⁴. C⁵ is a roller mounted on the channel C and carried by any suitable bearing parts C⁶.

It will be understood that while I have shown and described a practical operative device, nevertheless many changes and modifi-

cations might be made in the size, shape, number and disposition of parts without departing materially from the spirit of my invention. I wish therefore that my showing be taken as in a sense diagrammatic.

The use and operation of my invention are as follows:

When the device is to be used the parts are assembled as shown generally in the drawings. If the invention is embodied in a dryer, when the dryer is to be used, the door is moved into the position shown in Figure 2. In that position the roller which moves with the door, namely the roller B⁴, bears on the upper flange of the member C. The fixed roller, namely the roller C⁴, bears on the upper flange of the member B. The outward movement of the door may be limited by the stop B⁷. This part might be omitted and in that case the outward movement of the rack would be limited by the member B² which would contact directly with the roller. The effect of the two relatively movable rollers and the angle B and channel C is to provide a two-point support for the rack in which the two supporting points are sufficiently separate to hold the rack level even in the extreme outward extended position. When the material which is to be put on the rack has been put in place, the rack is moved again into the position shown in Figure 1. By this construction it is unnecessary to provide any overhead support for the rack or any bottom support. The rack is supported entirely from within the casing or housing by means of the rollers, the angle and the channel described, and it is therefore entirely self-contained.

I claim:

1. In combination in a movable supporting rack, a housing in which said rack is mounted and from which it may be moved outwardly and a supporting means for said rack, said supporting means including a fixed channel carried by said housing and having a roller positioned within it, and an angle member positioned on said rack, said angle member penetrating within said channel, there being a roller mounted on said angle member, the roller of the angle member bearing upon the upper flange of said channel and the roller mounted on said channel contacting the upper flange of said angle member.

2. In combination in a movable supporting rack, a housing in which said rack is mounted and from which it may be moved outwardly and a supporting means for said rack whereby the same is supported entirely from above, said supporting means including a fixed channel carried by said housing and having a roller positioned adjacent its outer end within it, and an angle member positioned on said rack and forming a part of it, said angle member penetrating within said channel, there being a roller mounted on said

angle member, the roller of the angle member bearing upon the upper flange of said channel and the roller mounted on said channel contacting the upper flange of said angle member, and a stop member carried by said angle member adapted to contact the fixed roller to limit the outward movement of the rack.

Signed at Chicago, county of Cook and State of Illinois, this 11th day of March, 1930.

FRANCIS T. JOHNSON.
